UNITED STATES PATENT OFFICE.

THOMAS W. H. MOSELEY, OF HYDE PARK, MASSACHUSETTS.

DESIGN FOR A BELL-TOWER.

Specification forming part of Design No. 5,117, dated July 11, 1871.

To all whom it may concern:

Be it known that I, THOMAS W. H. MOSELEY, of Hyde Park, in the county of Norfolk and State of Massachusetts, have invented a new and Improved Design for a Bell-Tower, of which the following is a specification:

The character of the design is represented in the accompanying drawing, which is an elevation of the same.

My bell-tower is made quadrangular in its horizontal section, with four corner-posts, A A, preferably of angle-iron, securely anchored in the earth at bottom and converging toward the top, where they are covered by a roof, B, which may be of any neat or ornamental character, and may be surmounted by a peak, I, and vane J or other device. At intervals in the height of the tower are placed horizontal braces or struts C C, which are secured to the posts A A, serving to strengthen them and keep them at the right distance apart. Crossing at the center of each of these horizontal braces C and firmly fastened at their ends to the posts A A are tie-bars D D. Tie-rods E E are stretched from the foundation

to near the top, each extending diagonally to the corner opposite that where it is attached at bottom. The base of the tower is surrounded by a casing, F, surmounted by a platform and balcony, G. H represents a stair-way passing in sections up each of the four sides of the tower in succession as many times as the height may require, and terminating at a gallery or platform, K, at top. Each successive flight of the said stair-way is varied in its length corresponding to the variations in height of the squares between the successive horizontal braces C C. L represents the bell suspended from a rod, M.

The manner of hanging the bell and other mechanical features in the structure will be made the subject of a separate application for a patent for construction.

I claim—

The design for a bell-tower, substantially as above set forth and shown.

THOMAS W. H. MOSELEY.
